CURTAIN FOR WARDROBE SECTIONS OF
LUGGAGEAry Kaufmann, South Orange, N. J., assignor to
K. Kaufmann & Co., Inc., a corporation of New
Jersey

Application February 10, 1936, Serial No. 63,126

2 Claims. (Cl. 190—41)

This invention relates to improvements in luggage, and the invention has reference, more particularly, to a novel construction and arrangement of curtain closure for the wardrobe sections of luggage.

In many types of modern luggage carriers, both of the larger kinds such as wardrobe trunks and in the hand or suitcase types of such carriers, means are provided for supporting garments in a neatly and compactly arranged condition within a separate section or compartment of the trunk or case; and in the hand luggage carriers such compartment is usually provided in connection with the cover section which is hinged to the main body of the case, a folding garment supporting frame of some sort being provided for supporting the garments and for moving the same into and out of the cover interior or compartment formed thereby.

It is an object of this invention to provide a novel arrangement and construction of curtain closure to cover the garments when folded into and supported within the compartment in which the same are to be carried; the novel curtain closure while broadly applicable to the garment containing section or compartment of any type of luggage carrier, is devised to offer especial advantages and adaptability as applied to the garment containing sections or compartments of hand luggage in the forms adapted for use by either ladies or gentlemen.

Another object of this invention is to provide a curtain closure which is elastically extensible, so as to draw snugly over the garments when the latter are folded into the receiving compartment therefor.

Another object of this invention is to provide means for securing the curtain closure in elastically stretched and closed condition; and, more specifically, the invention includes a novel curtain closure means cooperative with the collapsible stays which support the cover section of the carrier in open relation to the main body section thereof.

Other objects of this invention, not at this time more particularly enumerated, will become apparent in the following detailed description of the same.

Illustrative embodiments of this invention are shown in the accompanying drawings, in which:

Fig. 1 is a front elevation of a hand luggage carrier, the cover section of which provides a garment receiving compartment, the novel curtain closure means being provided in connection with

said cover section, and being shown as released subject to being thrown back over the margin of said cover section (as indicated by dotted lines), to thereby disclose and give access to the garment supporting means; Fig. 2 is a similar view, showing the curtain closure means secured in its closed condition; Fig. 3 is a vertical longitudinal section taken on line 3—3 in Fig. 2; Fig. 4 is a fragmentary enlarged vertical section taken on line 4—4 in Fig. 1; and Fig. 4A is a similar view of the luggage carrier closed and the curtain closure secured in its covering relation to the cover section of said luggage carrier.

Fig. 5 is a view similar to that of Fig. 2, but showing a modified form of curtain closure securing means, and Fig. 6 is also a view similar to that of Fig. 2, but showing a modified form of curtain closure means.

Similar characters of reference are employed in the hereinabove described views, to indicate corresponding parts.

Referring to the drawings, the reference character 10 indicates the main body section of a hand luggage carrier, and 11 indicates the cover section which is pivotally connected therewith by any suitable form of hinge connection 12, so as to open and close relative to said main body section. The body section is provided with the customary carrying handle 13, and cooperative locking elements 14. Cooperative with the cover section interior is any suitable form of garment supporting frame 15, many types and kinds of which are now familiar to the luggage industry. Connected between the interior faces of the side walls of main body section 10 and cover section 11, at each side of the carrier, are collapsible stay means, each set thereof comprising an arm 16 pivotally connected to the main body section, and an arm 17 pivotally connected to the cover section, the meeting ends of said arms 16—17 being pivotally joined together at 18 and being provided with means for yieldably holding the same in extended cover section supporting relation, as shown in Fig. 4, when said cover section is opened.

The novel curtain closure means, in one form thereof as illustrated in Figs. 1 to 5 inclusive, comprises a curtain body 19 which is preferably made of textile material, suitably secured by its upper end to the inside of the flange at the free end of said carrier cover section 11. Extending longitudinally from top to bottom ends of said curtain body 19, at least adjacent to each side marginal portion of the latter, and if desired, at one or more points laterally intermediate said side marginal portions, are elastic members or

straps 20 which are capable of longitudinal extension and contraction. These elastic members or straps may be of any suitable material or form so long as the same possess ability to stretch and contract longitudinally. For example, the same may consist of lengths of special metallic springs, elastic rubber straps, woven textile and rubber straps, or the like. The material of the curtain body, as related to the elastic members or straps 20, is shirred so as to be somewhat loosely gathered transversely, being thus capable of longitudinal extension and contraction in company with longitudinal stretch and contraction of said elastic members or straps 20. The upper ends of said elastic members or straps 20 are anchored together with the upper end of said curtain body 19 to the free end of said carrier cover section 11. The lower free end of the curtain body 19 and the lower ends of said elastic members or straps 20 are suitably secured to a comparatively rigid transverse bottom bar 21. Preferably said bottom bar 21 is enclosed in a binding member 22, which is doubled therearound so that the lower portions of the curtain body 19 and elastic members or straps 20 are received between the upper marginal portions 23 of said binding member 22, and thus secured or anchored thereto by stitching 24. Preferably, but not necessarily, the curtain body comprises two plies of material between which said elastic members or straps 20 are disposed. Suitably secured to and projecting endwise from the respective ends of said bottom bar 21 are headed studs or latch pins 25. The curtain closure means, in the form thus described, is, when released and contracted to its minimum length, somewhat less in length than the distance between the margins of the carrier cover section between which the same extends. The arms 17 of the collapsible stay means, with which the main body cover section of the carrier is provided, are each provided with latch stud or pin receiving slots 26 having entrance mouths 27 at the lower ends thereof which turn outwardly to open through the upper or outer margin of the arm 17. At their inner ends, said slots 26 are provided with laterally offset seats 28.

When garments are arranged in folded and supported relation to the frame 15, and disposed with the latter within the interior of the carrier cover section 11, the curtain body 19 is dropped downward to extend over the thus disposed garments. To secure the curtain body in closed condition, the bottom bar 21 is grasped and pulled downward, thereby longitudinally stretching the elastic members or straps 20 and the curtain body, so that the former are placed under tension, and in so doing the studs or latch pins 25 are thereupon respectively brought opposite the entrance mouths 27 of the respective receiving slots 26, and are pushed laterally into the latter. Upon accomplishing this, the bottom bar 21 is released so that longitudinal contraction of the tensioned elastic members or straps 20 will tend to yieldably draw upward the bottom bar thus causing the studs or latch pins 25 to ride upwardly in said slots 26, and into the seats 28 so as to be held thereby, and so that the curtain body 19 is thus secured in snug covering relation to the garments disposed within the carrier cover section 11, as shown in Figs. 2 and 3. The carrier cover section 11 may now be swung down into closed relation to main body section 10 of the carrier, the curtain closure being still held in the described garment covering relation (see Fig. 4A); and since the elastic

members or straps 20 remain under some tension tending to longitudinally contract the same, all tendencies of the lower end of the curtain body 19 to accidentally release itself from secured condition as obtained by the engaged relation of the studs or latch pins 25 with the receiving slots 26 and their seats 28 is adequately resisted.

One advantage which is especially attained by the above described preferred arrangement of curtain closure securing means, lies in the fact that a slot-like space 29 may be left between the lower end of the secured curtain closure and the adjacent margin of the carrier cover section 11 where it joins the rear end of said carrier main body 10, so that in the event extra long garments, such e. g. as ladies gowns, are packed, projecting extremities thereof may be allowed to extend through said slot-like space 29 for disposition within the rear interior portion of the carrier main body 10.

Referring to Fig. 5, there is shown therein a modified arrangement of means for securing the curtain closure in covering relation to the garments packed into the carrier cover section 11. This arrangement comprises a hook-like fastener 30 centrally secured to the hinged end of carrier cover section 11. Secured to said bottom bar 21 by a strap 31 adapted to adjustably engage its slotted buckle end 32 is an eye-member 33 adapted to be engaged and disengaged from said hook-like fastener 30, to thereby secure and release the curtain closure. It will also be understood that any other suitable or convenient curtain closure securing means may be utilized within the broader aspects of this invention.

Referring to Fig. 6, there is shown therein a modified form of curtain closure structure per se, the same comprising a main body 34 of flexible but substantially inelastic material, to the lower margin of which is secured, by stitching or in any other suitable manner, a transverse bottom section or panel 35 of elastic material capable of vertical extension and contraction. To the bottom or free marginal portion of said elastic section or panel 35 is suitably secured the comparatively rigid bottom bar 36. The bottom bar 36 may be provided with either type of curtain closure securing means already above described, or in fact any other suitable or convenient form of securing means. It will be obvious that the above described modified form of curtain closure will function in substantially the same manner as already hereinbefore described, since the elastic section or panel 35 thereof will provide for the elastic tensional stretch whereby the same is permitted to be engaged by the holding or securing means, and whereby, when so engaged, the same is held against accidental displacement or release from its closed and secured relation to the garment containing carrier cover section 11.

The novel curtain closure in the preferred first above described form thereof, provides, in addition to its functional utility a very novel and attractive appearance, contributing distinction and beauty to the carrier case, which is very desirable especially in connection with the types thereof designed principally for the use of women. This attractive appearance is effected by the shirring and gathering of the curtain body material, and may be also enhanced by panel effects attained by laterally spacing additional elastic members or straps between those employed at the side margins of the curtain body.

5 While the novel curtain closure has been shown and described specifically as employed in hand luggage wardrobe cases, it will be obvious that the same and the principles of construction thereof may also be utilized in other forms of luggage such as various types, sizes and kinds of wardrobe, steamer and automobile trunks and the like.

10 Changes other than those referred to may, of course, be made in the above described constructions, and many apparently widely different embodiments of this invention could be made without departing from the scope thereof as defined by the following claims. It is therefore intended 15 that all matter contained in the above description or shown in the accompanying drawings shall be interpreted as illustrative and not in a limiting sense.

I claim:—

20 1. A luggage carrier comprising a main body section, a cover section pivotally connected to said body section, stays connected to said sections at each side of said carrier for supporting said cover section in the open position thereof, 25 means for supporting garments within said cover section, a curtain body of textile or like material fixed by one end to said cover section at the free end thereof, laterally spaced elastic straps extending longitudinally from end to end of said 30 curtain body, said straps being anchored at the

fixed end of said curtain body, said curtain body being shirred along the location of said elastic straps whereby the same is transversely gathered subject to longitudinal movement with said elastic straps when the latter are stretched or contracted, a substantially rigid bottom bar to which the free ends of said curtain body and said elastic straps are secured, pins projecting from the ends of said bar, and said stays having slots for releasably receiving the pins of said bar to 10 secure said curtain to said stays at the opposite end thereof with said elastic straps under longitudinally stretched tension and said curtain body in extended closed relation to said cover section. 15

2. A luggage carrier comprising a main body section, a cover section pivotally connected to said body section, stays connected to said sections at each side of said carrier for supporting said cover section in the open position thereof, means for supporting garments within said cover 20 section, a curtain body fixed by one end to said cover section at the free end thereof, a substantially rigid bottom bar connected with the free end of said curtain body, pins projecting from the ends of said bar, and said stays having slots 25 for releasably receiving the pins of said bar to secure the free end of said curtain body to said stays and the curtain in extended closed relation to said cover section.
